UNITED STATES PATENT OFFICE.

HENRY BIRKETT BUCKLAND, OF NEWCASTLE-UPON-TYNE, ENGLAND.

STEAM-BOILER.

SPECIFICATION forming part of Letters Patent No. 449,244, dated March 31, 1891.

Application filed July 12, 1890. Serial No. 358,509. (No model.)

To all whom it may concern:

Be it known that I, HENRY BIRKETT BUCKLAND, a citizen of Great Britain, residing at Newcastle-upon-Tyne, in the county of 5 Northumberland, England, have invented certain new and useful Improvements in Steam-Boilers; and I do hereby declare the following to be a full, clear, and exact description of the invention, such as will enable others 10 skilled in the art to which it appertains to make and use the same.

My invention relates to improvements in steam-generators of a spherical form for use on land or sea and for various purposes.

15 The object of my invention is, among other things, to get a large amount of effective heating-surface by employing short tubes, to be able to use lighter plates and obviate the need of staying by the large use of spherical surfaces, and to economize the fuel and prevent smoke by employing an effective feed-water heater and arranging the flow of gases and admission of air in a peculiar manner, as hereinafter set forth.

25 Figures 1 and 2 show one form of boiler, Fig. 1 being a sectional elevation on C D, Fig. 2, and Fig. 2 a plan, partly in section, on line A B, Fig. 1. Figs. 3 and 4 show portions of the fire-box with corrugated inner plates. Figs. 30 5, 6, 7, 8, and 9 are drawn to a smaller scale and show modifications, which will be further referred to hereinafter.

In the above figures like parts are indicated by similar letters of reference.

35 The shell *a* is spherical, truncated at the bottom, which is filled in by a dished plate *c*, forming the furnace-crown. This plate is flanged to suit a spherical or partly-spherical combustion-chamber *b*, concentric with the 40 shell. The heating-surface of this chamber *b* may be increased by dividing it into two, three, or four different chambers, as shown in Figs. 6, 2, and 7, respectively, by vertical or other water spaces, or by suspending within 45 it a water-pot with circulating-tubes, as in Figs. 8 and 9, or close-ended or other tubes. The back plates *i* of the combustion-chambers are curved, as shown, to resist pressure. Smoke-tubes *j* radiate from chambers *b* to the 50 outside of shell to lead the products of combustion to the smoke-box. These tubes are

arranged in nests, according to the number of chambers *b*, space being left between the nests to allow access for cleaning, as shown in Fig. 2. In some cases extra tubes *k* are 55 fitted to lead a portion of the gases direct from furnace-crown *c* to lower portion of smoke-box, which is divided from the upper portion by a partition *n* to cause the gases entering at *k* to return to chambers *b* by the 60 lower series of tubes *j* and mix with the fresh gases in chambers *b*, all finally escaping together through the upper tubes.

The furnace portion of boiler is constructed of an inner and outer shell *f*, with end plates 65 *g*, forming a cylindrical, square, or other jacketed fire-box, which is connected by pipes to the shell *a*, either to form a portion of said boiler or a separate feed-water heater. In the latter case suitable valves are fitted. Figs. 70 3 and 4 show modifications of this fire-box with corrugated inside plates *f*. In Fig. 5 the cylindrical fire-box is shown formed with the spherical shell. These furnaces may be modified or adapted for coal, wood, petroleum, or 75 other fuel, or for forced draft either under the bars or through tubes *l* into the combustion-chambers, or both.

The tubes *l*, which are the lowest tubes leading into the fire-box, have the air admitted 80 to them through the pipes *L*, passing through the smoke-box, and the branch pipes *l'*.

What I claim is—

1. In a boiler, the combination, with the spherical shell, of the spherical combustion-chamber, the dished furnace-crown, and the radial fire-tubes inclined upwardly and downwardly from a central point and secured between the said combustion-chamber and shell, substantially as set forth. 85

2. In a boiler, the combination, with the spherical shell, of the spherical combustion-chamber, the dished furnace-crown, the radial fire-tubes *j*, arranged in separate series, and the water spaces, tubes, or legs inside the 95 combustion-chamber with their ends between the series of tubes, substantially as and for the purpose set forth.

3. In a boiler, the combination, with the spherical shell, of the spherical combustion-chamber, the dished furnace-crown, the radial fire-tubes *j*, and the tubes *k*, connecting the 100

said crown with the outer shell, substantially as set forth.

4. In a boiler, the combination, with the spherical shell, of the spherical combustion-chamber, the radial fire-tubes *j*, a smoke-box inclosing the outer ends of the said tubes, and the pipes *L*, provided with branches for introducing air through the lowest tubes, substantially as set forth.

10 5. In a boiler, the combination, with the spherical shell, of the spherical combustion-chamber, the dished furnace-crown, the radial fire-tubes *j*, the tubes *k*, connecting the furnace-crown direct with the outer shell, and 15 the smoke-box inclosing the ends of all the tubes and divided by a partition *n*, substantially as and for the purpose set forth.

6. In a boiler, the combination, with the spherical shell, of the truncated fire-box at

the base of the shell, the spherical combustion-chamber, the dished crown-plate, the radial fire-tubes inclined upwardly and downwardly from a central point and secured between the combustion-chamber and the outer shell, and a water-jacket encircling the fire-box and communicating with the main water-space of the boiler, substantially as and for the purpose set forth.

In testimony whereof I have affixed my signature in presence of two witnesses.

HENRY BIRKETT BUCKLAND.
